ELECTRIC SWITCH SENSITIVE TO SMALL OPERATING MOVEMENTS

Alfred Arnot, Warrington, England, assignor to
Aeronautical & Mechanical Investments Limited, a British company

Application April 30, 1943, Serial No. 485,220
In Great Britain April 23, 1942

2 Claims. (Cl. 200—153)

1

This invention comprises improvements in or relating to electric switches sensitive to small operating movements.

It is an object of this invention to provide an electrical switch mechanism which is sensitive to very small movements of the operating member. For example in the mechanism described in patent application No. 469,270, which comprises an electrical device for transmitting movement from a transmitter to a receiver such a switch mechanism is called for, and may be necessary both at the transmitter and at the receiver.

According to the present invention an electric switch mechanism comprises in combination a base, a contact-carrier pivotally mounted on the base and having a pallet-face in a plane to one side of the pivotal axis and facing away therefrom, a switch contact-member operatively connected to the contact-carrier so as to be operated when the contact-carrier rotates about its axis, and an actuating-member having a pallet-engaging portion which is mounted so as to be yieldingly pressed on the pallet face and to be so movable that the line of pressure can be shifted to one side of the contact-carrier pivot to actuate the contact-member in one direction, and to be returned to return the contact-member.

The actuating-member may be capable of being centered so that its line of pressure passes through the pivot axis and of being moved to either side to move the contact-member correspondingly, and the contact-member may engage two contacts, one when moved to one side and the other when moved to the other. Thus it is possible to make the switch member operate as a two-way switch with a neutral or off position in the centre, if desired, although it is within the scope of the invention to use the switch member for closing a single contact only.

Preferably the contact-carrier is further controlled by a spring mounted on the base in such a position as to act as a toggle-spring and thus to increase the certainty of movement of the contact-member into contact-engaging position.

The following is a description, by way of example, of one construction of switch mechanism in accordance with the invention:

In the accompanying drawing,

Figure 1 is a front elevation of an electric switch mechanism according to this invention;

Figure 2 is a plan;

Figure 3 is a diagrammatic perspective view of the switch mechanism and of one possible arrangement of parts and connections for automatic servo-operation.

2

The switch mechanism comprises an operating spindle 11 which is rotatably mounted and carries at one end a head 12 containing a transverse spring plunger 13 which constitutes a switch-actuating member, projects from one side of the head and has a knife edge 14, the line of which extends in a direction parallel with the axis of the operating spindle 11. Concentric with the spindle 11 and surrounding it, but mounted for independent rotation, is a circular switch base 15 of metal and on the switch base there is pivoted on a post 16, close to the spring plunger 13, a contact-carrier 17 in the form of an oblong block of metal having a pallet face 18 which engages the knife edge 14 on the spring plunger 13. The pallet-face 18 in its neutral position is at right-angles to the line of pressure of the spring plunger 13, the axis of the pivot-post 16 of the contact-carrier being in this position intersected by the line of pressure of the spring plunger 13 through the knife edge 14. The contact-carrier has a V groove 19 cut in one end and on the rotatable switch base there is an upstanding block 20 having another V groove 21 which faces the V groove 19 in the contact-carrier. Between the two V grooves there extends a piece of flat-section spring-steel 22 which is of curved or sinuous formation so that it constitutes a somewhat stiff compression spring, and the location of the parts is such that when the contact-carrier 17 is in its mid position with the line of pressure of the spring plunger 13 intersecting the axis 16 of the pivot the spring 22 which extends between the V grooves has a line of pressure which also intersects the axis 16 of the pivot. The spring 22 is thus a toggle spring, and while it does not prevent the spring plunger 13 from holding the contact-carrier 17 at rest in its central or normal position, it assists in pushing the contact-carrier over to one or other of its extreme positions immediately the spring plunger of the operating member is moved so that it presses either to one side or to the other of the axis of the contact-carrier 17.

From the other end of the contact-carrier 17 there extends a spring arm 23 which constitutes a contact-member and terminates in a double-sided contact 24. The contact 24 plays between two fixed insulated contact posts 25, 26 on the switch base. A bridge-piece 27 carries a bearing 45 for the end of spindle 11.

Therefore if the parts are in their normal position the axis of the spring plunger 13 of the operating spindle will intersect the pivot 16 of the contact-carrier 17 and the switch contact 24 55 will be held centrally between the two fixed con-

tacts 25, 26, without touching either of them. A very small angular deflection of the operating spindle 11 in either direction will cause the line of pressure to be altered and the switch contact will be brought firmly into engagement with one or the other of the contacts 25, 26 on the rotatable switch base. If such a switch mechanism is employed in apparatus of the kind described in the aforesaid patent application No. 469,270 the operating spindle 11 of the switch may constitute the control shaft on the receiver, as shown in Figure 3, and the switch base 15 may be connected to a follower shaft 28, by means of the bridge piece 27 or otherwise. This mechanism thus takes the place of the cam-closed switch contacts described in the aforesaid specification.

In Figure 3 the parts are similar to Figures 1 and 2 but the base 15 is shown as having gear teeth around its edge meshing with a pinion 29 on a shaft 30 of a reversible motor 31. The shaft 11 is operated in either direction by magnetic pawl-operating devices the pawls of which operate a ratchet wheel 32. The motor is connected by line 33 to a source of electric power 34 and by lines 35, 36 to the contact posts 25, 26. The contact 24 is connected by line 37 to the other terminal of supply. Thus when contact 24 is closed against 25 the motor 31 will operate in one direction and when closed against contact 26 the motor will operate in the other direction. The directions of movement are arranged to be such that the base 15 always tries to follow the shaft 11 and thus shaft 28 is motor-driven to the same extent of movement as shaft 11. The motor may be such as the one described in British patent application No. 6373/41.

The switch may also be used in a transmitter mechanism of the kind described in the alternative form of apparatus in the aforesaid specification No. 469,270, where the transmitter has a control shaft carrying spring contact arms.

In the mechanism herein described it is necessary that the spring loading behind the knife-edged plunger 13 on the operating spindle 11 should be great enough to ensure that the mechanism will re-set to neutral position, that is to say with the switch contact 24 out of engagement with either of the contacts 25, 26 on the switch base, after it has been displaced, when the operating spindle regains the position in which the plunger is in line with the axis of the contact-carrier. If the spring loading is sufficiently great

this will be attained. Stability may be further increased, at the expense of sensitivity, by slightly flattening the knife edge.

It will be appreciated that while a rotatable actuating member and rotatable switch base have been described the invention is applicable to other cases, for example where the switch base is fixed, or where one part (such as the actuating member) moves in a straight line relatively to the other part (such as the base) instead of being rotatably mounted.

I claim:

1. An electric switch mechanism comprising a base, a pivoted contact-carrier mounted on the base and having a pallet-face in a plane to one side of the pivotal axis and facing away therefrom, a switch contact-member carried by the contact-carrier so as to be operated when the contact-carrier rotates about its axis, an actuating member having a portion movable towards the pivot of the contact-carrier and means to press said pallet-engaging portion against the pallet-face of said contact-carrier, said actuating member being mounted so that its line of pressure passes through the axes of said pivot and is capable of movement to either side to move the contact-carried correspondingly, a pair of contacts adapted to be alternatively engaged by said contact-member depending on its direction of movement so that the contact member may act as a two-way switch member with a central neutral position, and a spring mounted on the base and engaging the contact-carrier in such a position as to act as a toggle-spring and thus to increase the certainty of movement of the contact-member.

2. An electric switch mechanism comprising in combination a rotatably mounted base, a contact-carrier pivoted on said base eccentrically to the center of rotation thereof and having a pallet-face facing towards the center of rotation of the base, a switch contact-arm extending from said contact-carrier, a contact on the base engageable by said contact-arm, a rotatable actuating member coaxial with the base, a pallet-engaging portion on the actuating member movable radially outward into contact with said pallet-face, resilient means for urging the pallet-engaging member toward said pallet-face, and a toggle compression spring mounted on said base and engaging said contact-carrier.

ALFRED ARNOT.
